UNITED STATES PATENT OFFICE.

CICERO HINE, OF CHICAGO, ILLINOIS, ASSIGNOR TO THE BRUNSWICK-BALKE-COLLENDER COMPANY, OF WILMINGTON, DELAWARE, A CORPORATION OF DELAWARE.

DESIGN FOR A GAME TABLE.

Application filed September 15, 1922. Serial No. 3,728. Term of patent 14 years.

To all whom it may concern:

Be it known that I, CICERO HINE, a citizen of the United States, residing at Chicago, in the county of Cook and State of Illinois, have invented a new, original, and ornamental Design for Game Tables, of which the following is a specification, reference being had to the accompanying drawing, forming a part thereof, in which the figure is a perspective view showing the invention.

I claim:

The ornamental design for a game table as shown.

CICERO HINE.
